UNITED STATES PATENT OFFICE

THOMAS CARLTON ROWEN, OF SWAMPSOFT, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY

FOLDING MACHINE AND METHOD

Application filed December 29, 1923, Serial No. 633,435. Renewed February 11, 1927.

The present invention relates to folding methods and machines, and more particularly to methods of and machines for folding a binding strip around the edge of a boot or shoe upper to which it is attached.

According to the method described in Letters Patent No. 1,589,718 to Andrew R. Ridderstrom, granted June 22, 1926, the upper is advanced over a support with its margin 10 bent out of the plane of the upper upward, in a direction away from the strip, and with the unsecured portion of the strip moved lightly across the secured-together edges. The strip is folded, step by step, around the secured-together edges, and the folded portions 15 of the strip are successively pressed against the upstanding bent edge and the margin along the other face of the sheet. A wiper is illustrated for wiping the strip across the secured-together edges prior to the folding and pressing operations, but it is found, in practice, that the wiper plays little, if any, function, and may be eliminated without perceptibly affecting the character of the resulting product.

The machine of the above-mentioned Letters Patent is more particularly designed for operation upon binding strips that are constituted of comparatively heavy or stiff material, like leather. When it is attempted to use a similar machine for the folding of binding strips constituted of comparatively lighter or flimsier material, like cloth, silk and the like, it is found that, if the wiper is dispensed with, the binding strip after folding, will be loose and baggy where it is sewed to the upper.

The reason for this different result will be readily understood when it is considered that the stock is fed forward in the machine by a feed point and a feed block, and that the strip is initially folded around the secured-together edges by a plow that is rigid with the feed block. The feed point is so designed as to clamp the margin of the upper against the feed block a little to one side of that portion of the edge of the upper that is near the plow. When the feed point comes down to clamp the stock against the feed block, therefore, the leather strip is caused by the plow

to exert a pulling action upon the edge of the upper, and it is this pulling action, in fact, that causes the edge of the upper to become bent up out of the plane of the upper, as before described.

This action is, however, a direct consequence of the leather strip being so comparatively heavy and stiff. When the strip is made of lighter and softer material, it can not exert the above-described pulling action 55 upon the edge of the upper. Instead, when the feed point comes down to clamp the stock against the feed block, the strip becomes buckled underneath the upper and becomes compressed, in buckled condition, against the 60 under face of the upper. It is this action which is believed to produce the loose and baggy effect before described.

It is therefore an object of the present invention to provide an improved method 70 and machine of the above described character that shall be adapted for operation upon binding strips of many different grades and materials.

With this end in view, a feature of the invention resides in engaging the upper and the strip at points where they are sewed together, so as to prevent the strip becoming buckled underneath the upper when the feed point 75 clamps the stock against the feed block.

To the attainment of this and other ends, the invention consists of the improved method and machine hereinafter described, illustrated in the accompanying drawing and defined in the appended claims.

The invention will be better understood by referring to the accompanying drawing, in which Fig. 1 is a perspective view of the upper, forward part of a machine constructed as described in the above-identified Letters 90 Patent and in Letters Patent No. 1,527,396 to the said Ridderstrom, granted February 24, 1925, but modified in accordance with the present invention, parts being broken away for clearness; Fig. 2 is a similar fragmentary 95 plan view, illustrating the operation of the machine shown in Fig. 1; Fig. 3 is a similar fragmentary perspective view, illustrating the folding action at a sharp, convex curve; Fig. 4 is an enlarged view of a preferred 100

combined feed block, biting projection and plow and its cooperating feed point; Fig. 5 is a sectional view of a shoe upper, showing a binding strip as it usually appears when attached to an edge of the upper; and Figs. 6 and 7 are sections similar to Fig. 4, illustrating steps in folding the binding strip around the shoe upper.

The invention is illustrated in the accompanying drawing in connection with the folding of a binding strip 2, of cloth, silk and the like, around the edge 4 of a sheet of leather or other material 6, such as a boot or shoe upper. An edge 8 of the binding strip is sewed to a face 10 of the shoe upper, along the edge 4, so that the sheet and the strip extend at an angle to each other from the secured-together edges 4 and 8. It will be understood that the invention is equally applicable to other articles than that which is herein chosen for purposes of illustration, that the binding strip may be constituted of other materials, including leather, and that the elements of the article need not necessarily be of the relative dimensions shown.

As in the machine of the above-described Letters Patent, the shoe upper 6 is initially placed upon a platform or support 24, with the face 10 of the upper in contact with the support. The free edge 26 of the strip 2 is initially moved lightly across and around the secured-together edges 4 and 8, into the space between an interior side face 28 of a feed point 30 and a plow 32 that stands up integrally from a plate 34 by which it is carried. The machine being set into operation, the upper is fed forward over the support 24, step by step, by a feed point 30 and a cooperating feed block 41. During the feeding, successive portions of the margin of the sheet, along the edge 4, are bent a little out of the plane of the sheet upward, or in a direction away from the strip, by a projection 38 that is shown standing up integrally from the feed block 41. As the sheet is fed forward, with its margin and the binding strip in this successively bent condition, successive portions of the strip 2 are initially intermittently folded around the secured-together edges 4 and 8 by the plow. The folded portions are then advanced by the feed point and the feed block to a fold presser 42, which presses down the initially formed folds against the bent-up edge 4 and against the margin of the sheet, along the face 16, as is shown in Fig. 7. These operations are continued in timed relation to each other until the whole strip has become folded.

The projection 38 rises gradually from the feed block at 39, and is provided with a more or less sharp edge 37 that engages the strip 2 and the sheet 6 at substantially the points where the strip is attached to the leather sheet, within the angle between the sheet and the strip. The feed point is provided with a

similar gradually rising part 35 that is adapted to cooperate with the gradually rising part 39 of the feed block to clamp the margin of the sheet 6, near the edge 4, in bent-up position, as before described. The remainder 31 of the active portion of the feed point is provided with gripping teeth to cooperate with the feed block 41 to clamp the portion of the sheet near the bent-up margin, and to feed the sheet 6 and the strip 2 forward over the support 24. When the feed point 30 comes down towards the feed block 41, therefore, the portion 35 of the feed point bends the margin of the sheet near the edge 4 against the portion 39 of the projection 38 and, in so doing, forces the edge 37 of the projection 38 to bite firmly into the sheet and the strip at the secured-together edges, as illustrated in Fig. 6. This prevents the strip 2 from becoming buckled under the sheet 6, where it would become compressed, in buckled condition, and held in buckled condition by the cement that is usually applied to maintain the strip folded against the face 16 of the sheet 6. Not only does the edge 37 prevent this buckling, however, but it actually produces, to a considerable degree, in connection with the movement of the feed point 30, the effect that is produced in the above-identified Letters Patent by the wiper. The projection 38 may, therefore, be termed a "wiper". The broader term "projection" will, however, be used in the specification and the claims because of the above-described function that it performs, and for which it is more particularly designed, of preventing the strip 2 from becoming buckled under the sheet 6.

Before leaving this part of the description, however, it should be noted that the feed point 30 is spring pressed downward towards the feed block by a spring 112, and is more fully described in the said Letters Patent No. 1,527,396, to the said Ridderstrom. The feed point 30, in addition to its feeding function, thus cooperates with the projection 38 in a manner somewhat analogous to the cooperation of the wiper and the retainer of the aforementioned Letters Patent. By reason of the fact that the feed point is intermittently raised and lowered, as is fully described in the said Letters Patent, the stock being advanced, step by step, between the lowering and the raising movements, the edge 37 of the projection 38 is caused to act intermittently, at spaced or separated portions only of the secured-together portions of the sheet and the strip. The cycle of operations is repeated many times a minute, the stock being fed forward a step at each cycle. As the steps of the feed are very short, however, the effect is practically the same as though the action were continuous.

Reference is made to the aforesaid Letters Patent for further details of construction, in-

cluding a description of the manner in which the feed block 41 and the feed point 30 are reciprocated towards and from the fold presser 42. It is not necessary to an understanding of the present invention to describe these details here, particularly as the invention may be carried out with machines that do not embody these details of construction. It is sufficient, for an understanding of the present invention, to state that during the backward movement of the feed block and the feed point from the fold presser 42, in the direction of the arrow of Fig. 2, the feed point first rises and then, towards the end of the backward movement, it descends again. It is during this backward movement that the plow folds the strip 2 around the secured-together edges; and it is during the final period of the backward movement, when the feed point descends, that the above-described operation of the projection 38 takes place, preventing the strips from becoming compressed against the under-face 10 of the sheet 6.

As is described in the above-mentioned Letters Patent, the plow 32 acts also as a gage. The plow of the present application is considerably hollowed out at 33 to enable it to receive the portion of the strip 2 that is adjacent to the secured-together edges, as is illustrated in Fig. 6. The comparatively large hollowed-out portion 33 would tend to interfere with the gaging action of the plow 32. This introduces no difficulty in the present machine, however, because the projection 38 necessarily acts also as a gage or guide.

In order to prevent the wiper and the plow of the machines disclosed in the aforesaid Letters Patent from causing the initially folded strip to contact with the edges 4 and 8, thereby preventing the folded strip from being pulled tightly around the secured-together edges, a separator 143 was provided, just in front of the plow, to maintain the cemented strip separated from the raw edges 4 and 8. The elimination of the wiper and the changed construction of the plow, together with the fact that the margin of the sheet is bent upward, make it less likely that the folded strip will stick prematurely to the secured-together edges, before it has been properly folded over. The separator 143 may therefore probably be dispensed with, though illustrated in the drawing.

The upper is advanced by the feed elements and the plow to a diagonally offset edge 144 of the fold presser 42, under which edge the initially plow-folded strip is positioned and by which it is pinched at the very fold against the upstanding bent edge 4. The pinched fold is later, after the next feed movement, pressed into even contact with the margin of the upper, along the face 16. The exterior surface of the fold presser is cylindrical, as shown at 156, so as to rock within a cylindri-

cal bearing 158 provided at the free end of an arm 160. The curvilinear working face 64 of the fold presser descends with a rolling action upon the strip. The previously pinched fold, after it is advanced, on the next feed movement, under the cylindrical face 164, is thus pressed out or rolled over, from the pinched portion outward towards the free edge 26 of the strip 2. The fold presser is spring-pressed towards the support 24 by a compression spring 166 mounted upon a rod 168 extending through an opening (not shown in the arm 160) and screw-threaded into the frame. By means of the screw threads, the pressure of the spring upon the arm 160 may be adjusted, the ends of the spring being confined between the arm and a knurled head 170 upon the rod 168. The working face 164 of the fold presser may be provided with teeth or may be otherwise roughened, to enable it to secure a firm grip upon the strip at thickened places, such as seams, thereby overcoming the tendency which the fold presser would otherwise have to push the stock away instead of ironing it out.

In the before-mentioned Letters Patent No. 1,589,718, the pressure exerted by the fold presser causes the bent-up edge 4 of the sheet to become compressed or crushed between the strip 2 and neighboring portions of the leather. This crushing action causes the strip 2 to be pulled tightly away from the upper 6 at the stitches 233 within the angle between the sheet and the strip. It is for this reason that the use of a wiper is really unnecessary in the machine of the said Letters Patent No. 1,589,718, since the tight pulling away of the strip 2 at the stitches 233 may be effected by the fold presser if the stock is properly presented thereto, as above described.

According to the machine of the present invention, the same tight pulling away of the strip 2 at the stitches 233 and the same crushing action, may be effected in the same way. It is preferred, however, to provide the fold presser 42 with a recess 29 in the face 64, just back of, and cutting into, the offset edge 144, as is illustrated more particularly in Fig. 7. The upstanding bent edge 4 and the strip 2 folded thereagainst are adapted to be received in the recess 29 during the pinching and rolling action of the fold presser before described, without destroying the tight pulling of the strip away from the upper 6 at the stitches 233. If the strip 2 were constituted of heavy leather, the resulting upstanding portion of the folded strip, along the edge, might be objectionable, because comparatively large. Using strips made of lighter material, the bunching along the folded edge is not so noticeable. The bunching is shown exaggerated, for clearness, in Fig. 7. This method of operation produces less strain upon the stock. The fold presser need not necessarily

have a curved face 164, but a flat recessed face will operate as well.

A toothed retainer point 246 is shown carried by a retainer 153 for holding the stock 5 against the support 24 to prevent the stock being pushed outward away from the operating instrumentalities of the machine and for holding the stock firmly against accidental movement during the return movement of the 10 feed elements. The retainer point need not necessarily be positioned as in the machines of the above-identified Letters Patent, and as is illustrated herein, at the rear of the plow 32. In fact, it is, for some purposes, advantageous to position the retainer point 246 forward and to one side of the position shown, 15 so as to enable the operator to hold the fingers closer to the other operating instrumentalities of the machine.

20 The description of many portions of the machine an understanding of which is not essential to an understanding of the present invention has purposely been omitted, and many parts of the machine have purposely 25 not been illustrated, in order not to distract the attention from the features of essential novelty. Fuller explanation of such portions of the machine will be found in the Letters Patent referred to above. It will be clear 30 that the features of novelty may be embodied in other machines, and in machines of other types, and that modifications may be made therein by persons skilled in the art, without departing from the spirit and scope of the 35 invention, as defined in the appended claims.

What is claimed is:

1. The method of folding a strip around 40 the edge of a sheet of material to one face of which, along the said edge, an edge of the strip is secured so that the sheet and the strip extend from the secured-together edges at an angle to each other, the said method comprising bending the margin of the sheet, along 45 the said edge, out of the plane of the sheet in a direction away from the strip, engaging with a member the bent portion of the sheet and the strip at the secured-together edges within the angle between the sheet and the strip, engaging with a member the margin of the sheet 50 near the said edge along the other face of the sheet, applying pressure to one of the members to cause the first-named member to bite into the sheet and the strip at the secured-together edges, folding the unsecured portion 55 of the strip around the secured-together edges, and pressing the folded portion of the strip against the said bent edge and the margin along the said other face of the sheet.

2. The method of folding a strip around 60 the edge of a sheet of material to one face of which, along the said edge, an edge of the strip is secured so that the sheet and the strip extend from the secured-together edges at an angle to each other, the said method comprising bending successive portions of the

margin of the sheet, along the said edge, out of the plane of the sheet in a direction away from the strip, engaging with the edge of an edged member the successively bent portions of the sheet and the strip at the secured-together edges within the angle between the sheet and the strip, engaging with a member the margin of the sheet near the said edge along the other face of the sheet, pressing upon the second-named member to cause the first-named member to bite into the said successively engaged portions of the sheet and the strip at the secured-together edges, folding the successive portions of the unsecured portion of the strip around the secured-together edges, and pressing the successively folded portions of the strip against the said bent edge and the margin along the said other face of the sheet.

3. The method of folding a strip around 85 the edge of a sheet of material to one face of which, along the said edge, an edge of the strip is secured so that the sheet and the strip extend from the secured-together edges at an angle to each other, the said method comprising engaging successive portions of the sheet and the strip at the secured-together edges within the angle between the sheet and the strip, and bending the portions of the margin adjacent to the said successive portions of the sheet, along the said edge, out of the plane of the sheet in a direction away from the strip, feeding the sheet and the strip, gaging the sheet and the strip along the engaged portions of the sheet and the strip, pressing upon the said portions of the margins to cause the said engaged portions to engage more tightly, folding the successive portions of the unsecured portion of the strip around the secured-together edges, and pressing the successively folded portions of the strip against the said bent edge and the margin along the said other face of the sheet.

4. The method of folding a strip around 110 the edge of a sheet of material to one face of which, along the said edge, an edge of the strip is secured so that the sheet and the strip extend from the secured-together edges at an angle to each other, the said method comprising feeding the sheet and the strip step by step, bending successive portions of the margin of the sheet, along the said edge, out of the plane of the sheet in a direction away from the strip when the sheet and the strip are fed to a predetermined position in the path of feed, intermittently engaging with a member the successively bent portions of the sheet and the strip at the secured-together edges within the angle between the sheet and the strip, intermittently engaging with a member the portions of the margin of the sheet near the said edge along the other face of the sheet, intermittently applying pressure to one of the members to cause the first-named member to bite intermittently into the

said successively engaged portions of the sheet and the strip at the secured-together edges, folding successive portions of the unsecured portion of the strip around the secured-together edges, and pressing the successively folded portions of the strip against the said bent edge and the margin along the said other face of the sheet.

5. The method of folding a strip around the edge of a sheet of material to one face of which, along the said edge, an edge of the strip is secured so that the sheet and the strip extend from the secured-together edges at an angle to each other, the said method comprising bending the margin of the sheet, along the said edge, out of the plane of the sheet in a direction away from the strip, clamping the bent portion of the sheet to hold it in bent position, engaging the bent portion of the sheet and the strip at the secured-together edges within the angle between the sheet and the strip, folding the unsecured portion of the strip around the secured-together edges, and pressing the folded portion of the strip against the bent edge and the margin along the other face of the sheet.

6. The method of folding a strip around the edge of a sheet of material to one face of which, along the said edge, an edge of the strip is secured so that the sheet and the strip extend from the secured-together edges at an angle to each other, the said method comprising bending successive portions of the margin, along the said edge, out of the plane of the sheet in a direction away from the strip, successively clamping the successively bent portions and adjacent portions of the sheet and feeding the sheet and the strip forward, engaging the successively bent portions of the sheet and the strip at the secured-together edges within the angle between the sheet and the strip, folding successive portions of the unsecured portion of the strip around the secured-together edges, and pressing the successively folded portions of the strip against the bent edge and the margin along the other face of the sheet.

7. A machine for folding a strip around the edge of a sheet of material to one face of which, along the said edge, an edge of the strip is secured so that the sheet and the strip extend from the secured-together edges at an angle to each other, the said machine having, in combination, means for bending the margin of the sheet, along the said edge, out of the plane of the sheet in a direction away from the strip, a member for engaging the bent portion of the sheet and the strip at the secured-together edges within the angle between the sheet and the strip, a member for engaging the margin of the sheet near the said edge, along the other face of the sheet, means for applying pressure to one of the members to cause the first-named member

to bite into the sheet and the strip at the secured-together edges, and means for folding the unsecured portion of the strip around the secured-together edges and for pressing the folded portion of the strip against the said edge and the margin along the said other face of the sheet.

8. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet with the margin of the sheet, along the said edge, bent out of the plane of the sheet in a direction away from the strip and with the unsecured portion of the strip moved across the secured-together edges, the feeding means comprising two members, one for engaging the bent portion of the sheet and the strip at the secured-together edges within the angle between the sheet and the strip, and the other for engaging the margin of the sheet near the said edge along the other face of the sheet, means for moving the members towards each other to grip the stock and to cause the first-named member to bite into the sheet and the strip at the secured-together edges, means for folding the strip around the secured-together edges, and means for pressing the folded strip against the bent edge and the margin along the said other face of the sheet.

9. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet with the margin of the sheet, along the said edge, bent out of the plane of the sheet in a direction away from the strip and with the unsecured portion of the strip moved across the secured-together edges, a member for engaging the bent portion of the sheet and the strip at the secured-together edges within the angle between the sheet and the strip, the feeding means comprising a member for engaging the margin of the sheet near the said edge along the other face of the sheet, means for moving the members towards each other to cause the first-named member to bite into the sheet and the strip at the secured-together edges, means for folding the strip around the secured-together edges, and means for pressing the folded strip against the bent edge and the margin along the said other face of the sheet.

10. A machine for folding a strip around the edge of a sheet of material to one face of which, along the said edge, an edge of the strip is secured so that the sheet and the strip extend from the secured-together edges at

- an angle to each other, the said machine having, in combination, a feed block and a feed point for feeding the sheet and the strip, the feed block having a projection for bending the margin of the sheet, along the said edge, out of the plane of the sheet in a direction away from the strip and for engaging the bent portion of the sheet and the strip at the secured-together edges within the angle 70
 10 between the sheet and the strip, the feed point being shaped to cooperate with the feed block to clamp the bent margin against the feed block and to cause the projection to bite into the sheet and the strip at the secured- 75
 15 together edges, a plow for folding the strip around the secured-together edges, and a fold presser for pressing the folded strip against the bent edge and the margin along the other face of the sheet.
 20 11. A machine for folding a strip around the edge of a sheet of material to one face of which, along the said edge, an edge of the strip is secured so that the sheet and the strip extend from the secured-together edges 80
 25 at an angle to each other, the said machine having, in combination, a feed block and a feed point for feeding the sheet and the strip step by step, a member for bending the margin of the sheet, along the said edge, out of 85
 30 the plane of the sheet, in a direction away from the strip, and for engaging the bent portion of the sheet and the strip at the secured-together edges within the angle between the sheet and the strip, means for moving 90
 35 the feed point towards the feed block to clamp the sheet against the feed block and for moving the feed point from the feed block to release the sheet, whereby the strip is separated from the sheet by the member when 95
 40 the feed point clamps the sheet against the feed block, and means for folding the strip around the secured-together edges and pressing the strip into contact with the other face 100
 45 of the sheet.
 50 12. A machine for folding a strip around the edge of a sheet of material to one face of which, along the said edge, an edge of the strip is secured so that the sheet and the strip extend from the secured-together edges at an 105
 55 angle to each other, the said machine having, in combination, a feed block and a feed point for feeding the sheet and the strip step by step, the feed point and the feed block having portions for clamping portions of the sheet 110
 60 to one side of the edge of the sheet in the plane of the sheet, and having portions for bending the margin of the sheet along the said edge out of the plane of the sheet in a direction away from the strip and for clamping the bent portions in bent position, means for moving the feed point towards the feed block to clamp the sheet against the feed block, and for moving the feed point from the feed block to release the sheet, means for engaging the sheet 115
 65 and the strip at the secured-together edges.

within the angle between the sheet and the strip when the feed point is moved towards the feed block, and means for folding the strip around the secured-together edges and for pressing the strip against the bent-up edge 70
 75 and the other face of the sheet.

13. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet and the strip with the margin of the sheet, along the said edge, bent out of the plane of 80
 the sheet in a direction away from the strip and with the unsecured portion of the strip moved across the secured-together edges, a plow for folding the strip around the secured- 85
 together edges, and a fold presser for pressing the folded strip against the bent edge and the margin along the other face of the sheet, the fold presser having a recess for receiving the bent edge of the sheet and the strip folded thereagainst.
 90

14. A machine for folding a strip around the edge of a sheet of material to one face of which, along the said edge, an edge of the strip is secured so that the sheet and the strip extend from the secured-together edges at 95
 an angle to each other, the said machine having, in combination, means for feeding the sheet and the strip with the margin of the sheet, along the said edge, bent out of 100
 the plane of the sheet in a direction away from the strip and with the unsecured portion of the strip moved across the secured-together edges, a member for engaging the bent portion of the sheet and the strip at the secured-together edges within the angle between the sheet and the strip, a plow for 105
 folding the strip around the secured-together edges having a hollowed-out portion for receiving the portion of the strip adjacent to the secured-together edges, and a fold presser for pressing the folded strip against the bent edge and the margin along the other face of the sheet, the fold presser having a 110
 recess for receiving the bent edge of the sheet and the strip folded thereagainst.
 115

15. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet and the strip comprising a member for bending the margin of the sheet, along the said edge, out of the plane of the sheet in a direction away from the strip and for engaging the sheet and the strip at the secured-together edges, the said member having means for folding the strip around 120
 125
 the secured-together edges.
 130

16. A machine for folding a strip around the edge of a sheet of material to one face of which, along the said edge, an edge of the strip is secured so that the sheet and the strip extend from the secured-together edges at an angle to each other, the said machine having, in combination, means for feeding the sheet and the strip comprising a member for bending the margin of the sheet, 10 along the said edge, out of the plane of the sheet in a direction away from the strip and for engaging the sheet and the strip at the secured-together edges, the said member constituting a gage and having means for folding the strip around the secured-together edges, and means for pressing the folded strip against the bent-up edge and the other face of the sheet.

In testimony whereof, I have hereunto 20 subscribed my name this 27th day of December, 1923.

THOMAS CARLTON ROWEN.
